UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM FOR MULTISHUTTLE LOOMS.

Application filed March 3, 1926. Serial No. 92,037.

This invention relates to a weft replenishing mechanism particularly adapted for use in a loom having a plurality of shuttle boxes at both ends thereof. A loom of this type 5 is shown in my prior application, Serial No. 16,791 filed Mar. 19, 1925.

While my improvements have been worked out with special reference to the loom shown in said application, many features of the invention are of more general application and are not limited in their utility to this particular type of multi-shuttle loom.

One important object of my invention is to provide an improved weft carrier magazine together with novel and improved devices for releasing a weft carrier therefrom.

A further object is to provide an improved weft carrier holder effective to receive a selected and released bobbin and to advance 20 it to transfer position.

Another important feature of the invention relates to the provision of a novel and improved transfer mechanism for the selected weft carrier.

25 My invention further relates to arrangements and combinations of parts which will be hereinafter described and more particularly pointed out in the appended claims.

A preferred form of the invention is 30 shown in the drawings in which

Fig. 1 is a right hand side elevation of a loom embodying my improvements;

Fig. 2 is an enlarged side elevation of certain of the parts shown in Fig. 1;

35 Fig. 3 is a partial sectional elevation, showing the magazine from the opposite side;

Fig. 4 is a detail sectional front elevation, taken along the line 4—4 in Fig. 3;

40 Fig. 5 is a side elevation of certain cam mechanism to be described;

Fig. 6 is a similar view, showing the parts in a different position;

Fig. 7 is a detail sectional view, taken 45 along the line 7—7 in Fig. 4;

Fig. 8 is a detail plan view of the bobbin holder;

Fig. 9 is a detail sectional view, taken 50 along the line 9—9 in Fig. 8; and

Fig. 10 is a detail sectional view through the rotary shuttle boxes.

Referring to the drawings, I have shown my improvements embodied in a loom having a loom side 10 (Fig. 1), a crank-

shaft 11, connecting rods 12, and a bottom 55 or cam shaft 13, together with the usual lay 14 (Fig. 3) and breast beam 15, all of these parts being of the usual construction. The lay 14 is provided at its left hand end with the usual drop boxes and at its right hand 60 end with shuttle boxes mounted in a rotary carrier and actuated by mechanism substantially similar to that shown in the prior application above referred to.

For the purposes of this application, it is 65 sufficient to state that the lifter rod 16 (Fig. 2) supports a pair of rack bars 17 which selectively engage a pinion 18 secured to the rotary shuttle box support 19. As the lifter rod 16 is raised or lowered, the rack bar 70 17 is selectively engaged with the pinion 18 and rotates the support 19 to bring the desired shuttle box in operative position at the top of the support.

Both the shuttles S and the shuttle boxes 75 are open from top to bottom as clearly shown in Fig. 10 and the fixed shaft or bearing 110 for the rotary support 19 is slotted vertically as indicated at 111 in Fig. 10 to provide a clear vertical passage for the 80 downward movement of the ejected bobbins B. It will be noted that the uneven number of shuttle boxes always provides a space below the opening 111 for the further ejection of the exhausted bobbin.

I have also provided a guide member 20 85 (Fig. 2) mounted on the lay 14 above the rotary support 19 and having guide-ways 21 for a vertically movable transerrer 22. A spring 23 holds the transerrer normally 90 raised against an adjustable stop 24. The transerrer is moved downward by mechanism to be described, when it is desired to replenish an exhausted weft carrier in the running shuttle.

The weft carrier magazine M (Fig. 2) is 95 of special construction and comprises end plates 25 and 26 (Fig. 3) having ribs (not shown) forming the usual vertical compartments for weft carriers of different kinds or colors. The lowermost weft carrier in each compartment is supported by a cradle or releasing device 27 (Figs. 4 and 7).

Each releasing device 27 is fixed on a cross rod 28 (Fig. 4) having bearings in 105 the magazine side members 25 and 26. A similar support (not shown) is provided on the rod 28 for the tip end of the bobbin.

The supporting members are yieldingly held in operative position, (as indicated in Fig. 7) by coil springs 29 having one end thereof secured to fixed points on the magazine.

5 Each releasing member 27 extends under and beyond the magazine side plate 26 and has a bearing portion 30 fixed to the end of the rod 28. A lug 31 projects laterally from each bearing portion 30 and is positioned under one of a series of bell cranks 32 (Fig. 3) pivoted on studs 33 in the magazine side 26.

10 The upper ends of the bell cranks 32 are connected by a bar 34 to a lever 35 mounted 15 on a fixed pivot 36. A link 37 is pivoted on a stud adjustably secured in a slot 38 on the lower end of the lever 35 and is connected to an arm 40 on a rock shaft 41.

15 The shaft 41 extends along the breast beam 15 to the left hand side of the loom, where it is controlled by weft detecting mechanism of any convenient construction.

20 This mechanism forms no part of my present invention and it is sufficient to state that 25 the shaft 41 is rocked in the direction of the arrow *a* in Fig. 3 upon indication of weft exhaustion in the shuttle about to be picked to the magazine side of the loom.

25 The bell cranks 32 are spaced from the 30 lugs 31 so that they cannot directly engage the lugs when rocked by the lever 35. A spacing block 42 is yieldingly and pivotally mounted at 43 (Figs. 3 and 4) on an upward extension 44 formed on a rearwardly extending portion 45 of the bobbin holder 46. The bobbin holder is provided 35 with a split hub 47 (Fig. 4) by which it is clamped to the upper end of a supporting rod 48 pivoted at 49 (Fig. 1) in substantial 40 alignment with the usual rock shaft upon which the lay is supported.

45 The bobbin holder 46 is provided with recesses 50 and 51 (Fig. 8) to receive the bobbin or weft carrier *W* which is to be advanced to transfer position and the bobbin is supported in the recesses by a pair of springs or spring plates 52 (Fig. 9) at each 50 end thereof. These springs are adapted to yield and release the weft carrier when it is forced downward by the transerrer 22.

55 Special mechanism is provided for positioning the bobbin holder 46 so that it will receive a bobbin or weft carrier corresponding to the running shuttle in its recesses 50 and 51. For this purpose the supporting rod 48 (Fig. 1) is connected by a link 53 to a bell crank 54, the connection including an elongated slot in the link 53 to permit lost motion, as will be hereinafter 60 described.

65 The bell crank 54 is connected by a link 55 to an arm 55^a mounted on a rock shaft 55^b which extends to the opposite side of the loom, where it is connected with the usual drop box mechanism so that the arm 55^a will

be moved in unison with the rise and fall of the usual drop boxes at the left hand side of the loom.

This drop box mechanism may be of any usual or commercial form and it is believed 70 to be unnecessary to specifically describe the construction or operation thereof in this application. As the arm 55^a moves with the drop boxes it acts through the link 55, bell crank 54 and link 53 to swing the supporting 75 rod 48 forward or back to present the bobbin holder 46 under the magazine compartments corresponding to the running shuttle.

As the bobbin holder 46 is thus moved under a selected magazine compartment the 80 block 42 associated with the bobbin holder is moved to a position over the lug 31 of the releasing member 27 in the same magazine compartment, thereby rendering the associated bell crank 32 operative to release a 85 bobbin therefrom.

In addition to the mechanism for thus selectively positioning the bobbin holder, I have provided mechanism for advancing the bobbin holder to transfer position prior to 90 the operation of the transerrer 22. For this purpose, I have provided a collar 56 on the link 53 which is engaged by the forked end of a lever 57 pivoted at 58 and having an 95 arm 59 connected by a link 60 to a cam lever 61. The connection between the link 60 and the lever 61 is preferably made adjustable as indicated in Fig. 1.

The cam lever 61 is pivoted at 62 and is provided with a cam roll 63 which is positioned in the groove or track 64 (Fig. 5) of a special double-acting cam 65 mounted on the bottom or cam shaft 13. The normally operative portion of the track 64 of the cam 65 is substantially circular, so that the lever 61 remains stationary when the cam roll is positioned in the circular portion of the cam track.

The cam 65 is provided, however, with outwardly extended track portions 66 which at times receive the roll 63 and give the cam lever 61 an operative movement. Pivot gate fingers 68 normally occupy the positions indicated in Fig. 5 and are yieldingly retained in such positions by springs 69. 115 Each finger 68 is provided, however, with a pin 70 extending into position for engagement by a lever 71 (Fig. 5) mounted on a fixed pivot 72.

The lever 71 is normally held out of position for engagement with the stud 70 by a spring 73 but may be advanced as herein-after described to the position indicated in Fig. 6, in which position one of the fingers 68 will be swung inward to the position indicated at the right in Fig. 6, thus causing the cam roll 63 to traverse the extended portion 66 of the cam track. I thus give the lever 61 a movement which is effective 125 through the connections previously described 130

to swing the bobbin holder 46 rearward to transfer position.

Additional fingers 74 are provided at the rear portions of the track extensions 66. 5 These additional fingers 74 are also yieldingly held in out of position by the springs 69 but will yield inwardly to permit the cam roll 63 to pass out of either one of the track extensions 66, after being admitted thereto 10 by inward movement of one of the corresponding fingers 68.

The lever 71 is suitably connected as by a wire or cord 76 (Fig. 1) to an arm 77 on the rock shaft 41 previously described. As the 15 rock shaft 41 is moved to release a weft carrier from the magazine, the lever 71 will be advanced to the position indicated in Fig. 6 and the subsequent rotation of the cam 65 will cause one of the fingers 68 to be pressed 20 inward, after which the cam roll 63 will traverse the cam extension and act through the connections previously described to advance the holder carrying the bobbin which has been released to position said bobbin under the transerrer 20.

The means for actuating the transerrer is best shown in Fig. 3 and comprises a lever 80 having a lug or projection 81 normally positioned above a cam roll 82 mounted on 30 the transerrer 22. The lever 80 is pivoted at 82^a on the magazine frame and is normally held in raised position against a stop pin 83 by a spring 84.

A hook 85 is pivoted at 86 on the lever 80 35 and extends downward adjacent a hook 87 on the upper end of a plunger 88. The plunger 88 (Fig. 1) is connected by a give-way device 89 to a cam lever 90 having a cam roll 91 positioned in the track of a double-acting cam 92 on the cam shaft 13. The plunger 80 is thus given a regular reciprocation upon every revolution of the crankshaft 11 which is geared 2 to 1 to the cam shaft 13. The connections of the give-way 89 to 40 the lever 90 is preferably adjustable to vary the throw of the plunger 80 if desired.

The hook 85 (Fig. 3) is normally held against a stop pin 94 by a spring 95, in 50 which position it is out of the path of the hook 87. The hook 85 is also provided with a leaf spring 96 engaged by a bell crank 97 pivoted at 98 on the magazine frame and connected by a link 99 to the arm 40 previously described, the connection between 55 the bell crank 97 and the link 99 preferably permitting of a considerable amount of lost motion.

When the arm 40 is swung outward in the direction of the arrow *a* the bell crank 97 60 will be rocked, forcing the rearwardly extended upper arm of the bell crank downward against the spring 96 and swinging the hook 85 into the path of the hook 87 which is then in raised position. The arm of the bell crank 97 is then received in a depressed

portion 100 at the lower end of the spring 96 and remains in holding engagement while the lost motion connection with the link 99 permits the arm 40 to return to its normal position. 70

The plunger 88 thereupon acts through the hook 85 to draw the lever 80 downward during the forward movement of the lay 14, thus depressing the transerrer 22 and effecting replenishment of the weft carrier in 75 the active shuttle. During this movement the spring 96 moves downward out of engagement with the bell crank 97, so that the hook 85 will be disengaged from the hook 87 at the end of the return upward movement. As the lay approaches front center, the cam roll 82 on the transerrer runs off of the front end of the lug or projection 81 on the lever 82 and the transerrer immediately returns to the raised position before the 80 lever 80 is released. 85

Having thus described the details of construction of my improved weft replenishing mechanism and the operation thereof, it is believed that the construction will be readily understood and that further and separate description of the general operation is unnecessary. I do not wish to be limited, however, to the details herein disclosed, but what I claim is:— 90

1. In a weft replenishing multi-shuttle loom, a stationary magazine having a plurality of bobbin compartments each having a separate discharge opening at its lower end, a bobbin holder movable beneath said discharge openings and having a single bobbin holding recess therein, a lay having a plurality of shuttle boxes mounted at the magazine end thereof, said boxes being movable to present a selected shuttle box in running position and each selected box thus positioned being substantially unobstructed above and below to permit free vertical replenishment of an unexhausted bobbin in a shuttle boxed therein, means to selectively 105 position said bobbin holder under any one of said discharge openings, selective means to release a bobbin from the corresponding compartment, and means to thereafter advance said bobbin holder and bobbin to 110 transfer position over said running shuttle box. 115

2. The combination in a loom as set forth in claim 1, in which means is provided for thereafter transferring said selected bobbin 120 from said bobbin holder to said running shuttle.

3. The combination in a loom as set forth in claim 1, in which means is provided on the lay for thereafter transferring said selected bobbin from said bobbin holder to 125 said running shuttle.

4. The combination in a loom as set forth in claim 1, in which a transerrer is mounted on the lay above the running shuttle, and 130

in which means is provided for depressing the transferrer as the lay approaches front center, to thereby transfer a bobbin from said bobbin holder to the running shuttle.

5. The combination in a loom as set forth in claim 1, in which a transferrer is mounted on the lay above the running shuttle, and in which means is provided on the loom frame for depressing said transferrer as the lay approaches front center, said transferrer being freed from said depressing means at front center and being immediately returned to raised position.

6. The combination in a loom as set forth in claim 1, in which a transferrer is mounted on the lay above the running shuttle, and in which means is provided on the loom frame for depressing said transferrer as the lay approaches front center, said transferrer being freed from said depressing means at front center and a spring being provided to immediately return said transferrer to raised position before substantial rearward movement of the lay.

25. 7. The combination in a loom as set forth in claim 1, in which the bobbin holder is selectively positioned beneath the magazine in predetermined relation to the movements of the shuttle boxes to and from running position.

8. The combination in a loom as set forth in claim 1, in which the bobbin holder is selectively positioned beneath the magazine in predetermined relation to the movements 35 of the shuttle boxes to and from running position, and in which additional means is provided for thereafter moving said bobbin holder from its selected position to a common transfer position above the running 40 shuttle box.

9. The combination in a loom as set forth in claim 1, in which the bobbin holder is selectively positioned beneath the magazine in predetermined relation to the movements 45 of the shuttle boxes to and from running position, and in which additional means is provided for thereafter moving said bobbin holder from its selected position to a common transfer position above the running

shuttle box, said additional means being rendered operative by indication of weft exhaustion in the shuttle about to enter the running shuttle box adjacent the magazine.

10. In a weft replenishing loom, a stationary magazine having a plurality of separate bobbin compartments, a separate bobbin retaining device closing each compartment at its lower end, an actuator for said retaining devices, inoperatively spaced therefrom, a bobbin holder, selective means to position said holder under said magazine compartments, and an element movable by said holder to form a connection between said actuator and the retaining device associated with the bobbin compartment under which 65 said bobbin holder is selectively positioned.

11. In a weft replenishing loom, a stationary magazine having a plurality of separate bobbin compartments, a separate bobbin retaining device closing each compartment 70 at its lower end, an actuator for said retaining devices, inoperatively spaced therefrom, a bobbin holder, selective means to position said holder under said magazine compartments, and an element movable by said holder to form a connection between said actuator and the retaining device associated with the bobbin compartment under which 75 said bobbin holder is selectively positioned, said element being thereafter movable with 80 said actuator and said retaining device.

12. In a weft replenishing loom, a stationary magazine having a plurality of separate bobbin compartments, a separate bobbin retaining device closing each compartment 85 at its lower end, a separate actuating member for each retaining device, a bobbin holder and means to give all of said actuating members in unison a normally inoperative movement, said bobbin holder being selectively effective to render one of said actuating members operative to move the retaining device from beneath the compartment with which said bobbin holder is at any time positioned to co-operate.

In testimony whereof I have hereunto affixed my signature.

ALBERT A. GORDON.
